DRAFT RIGGING

John D. Fenstermacher, Piedmont, and Bowater
B. Sumner, Burlingame, Calif.

Application March 11, 1931. Serial No. 521,846

6 Claims. (Cl. 213—61)

This invention relates to draft rigging for railway cars, and more particularly to a combined draft sill and drawbar stop construction of the type in which the draft rigging is enclosed between a pair of separated sills or beams and the shank of the coupler is slidingly supported therebetween.

One of the objects of this invention is to provide an improved means for connecting and spacing the front ends of the draft sills by a single link.

Another object is to provide a novel means for mounting and retaining the draft sill connecting link.

15 A further object is to provide a draft sill structure of improved design for use with a single connecting and spacing link.

In the drawing:

Figure 1 is a side elevation of a draft rigging embodying this invention.

Figure 2 is a front view thereof.

Figure 3 is an enlarged fragmentary detail of the forward end of one of the sills showing the link with its head broken away.

25 Figure 4 is a plan of the connecting link.

Figure 5 is a sectional view taken on the line V—V of Figure 4.

Referring more particularly to the drawing, the numeral 2 designates the main side members 30 or sills of the draft rigging which are preferably of cast steel and are attached to the car structure in any suitable manner.

The draft sills are separated a sufficient distance and are suitably shaped to receive the usual spring draft gear. The forward ends of these draft sills are connected together by a removable cross-bar or link 4 which is so designed and mounted that it also serves to hold the forward ends of the draft sills in spaced 40 relation.

Each of the draft sills is provided with a hook 5 cast integral with the sill at the lower front corner. The opening of the hook 5 faces toward the front and at an angle of about 45 degrees above the horizontal. The front and back inside walls of the hook are parallel to this direction of facing, and the bottom 6 of the hook is rounded on the inside to receive the rounded portion 7 of the bar or link 4.

50 The back or rear wall of the hook is provided with an integral lug 8 which extends transversely the entire width of the hook.

The hooks 5 have one of their side walls tapered downwardly and inwardly to provide a wedge-like surface adapted to cooperate with

the bar or link 4 to form a tight fit, as is hereinafter described.

The hook is provided with a hole 9 adjacent its free end to receive a cotter-pin or other key member 10 to prevent accidental movement of 60 the bar or link 4 out of the hook.

The inside walls of the hook taper downwardly and inwardly to provide for wedging the bar or link 4 in position.

The bar or link 4 is so designed as to engage 65 in the hooks 5 and, as stated before, form a connecting and spacing link between the draft sills to prevent their spreading or coming together in service. These links may be either cast, forged or machined, and are preferably 70 formed from steel. The center portion of the bar or link 4 is preferably of square or rectangular cross-section in order that a wrench may be readily applied for manipulating it.

The bars or links 4 are provided with heads 12 75 at each end having flat inside faces adapted to engage the outer side walls of the hooks 5. The bars or links are cut away adjacent each end to form bearing portions 13 adjoining the heads 12 and to provide a shoulder 14 adapted to 80 engage the inner side faces of the hooks.

The bearing portions 13 of the bars or links each have a rounded bearing surface 15 adapted to be seated on the rounded bottom 6 of the hook and relatively short straight portions 16 85 adapted to extend parallel with the front and back walls of the hook when the bar or link is seated in operative position. The bearing portions 13 of the bars are further cut away at right angles to the straight portions 16 to form 90 a flat surface 17 adapted to be engaged with the flat under side of the lugs 8. The pin or key 10 prevents the bar or link moving or backing out of the hooks after it is once seated.

When mounting the link 4 it is simultaneously 95 engaged in the hooks 5 on both sills 2 with the flat surfaces 17 facing the lugs 8, and the link 4 is then moved down into the hooks. The link is then turned in the hooks to locate the rounded surfaces 15 on the rounded bottoms 100 of the hooks and to bring the flat surfaces 17 up against the flat lower faces of the lugs 8. The pins or keys 10 are then inserted in the holes 9 in the hooks and these pins in combination with the lugs 8 securely lock the link 105 in place. As the bearing portions 13 of the links 4 are disposed in the hooks 5, the flat inner faces of the heads 12 and the shoulders 14, which are parallel therewith, will engage and grip the tapered side walls of the hooks in such 110

manner as to insure a tight fit, thus eliminating unnecessary wear.

The link 4, besides serving as a connecting and spacing link, also serves as an auxiliary support for the coupler or draft gear.

While we have shown and described one certain embodiment of our invention, it will be understood that we do not wish to be limited thereto since various modifications may be made 10 by those skilled in the art without departing from the scope of our invention, as defined in the appended claims.

We claim:

1. In a draft rigging for railway cars, a pair 15 of draft sills, said sills being separated from their forward ends rearwardly for an appreciable distance to receive the draft rigging between them, hook-shaped members adjacent the lower forward end of each of said sills, a single 20 one-piece bar removably mounted in said hook-shaped members for connecting and spacing said sills and means forming a wedging fit between said bar and said hooks.

2. In a draft rigging for railway cars, a pair 25 of draft sills, said sills being separated from their forward ends rearwardly for an appreciable distance to receive the draft rigging between them, a hook member formed integral with each of said sills adjacent its forward lower end, said hooks facing toward the forward end of said sills and opening at an angle above the horizontal, each of said hooks having one of its side walls tapered downwardly and inwardly and a single one-piece bar removably mounted 30 in said hooks for connecting and spacing said sills, said bar being provided with head members at each end and being cut away adjacent each end to form bearing portions adjoining said heads and adapted to enter said hooks, a 35 shoulder at the inner end of each of said bearing portions, said shoulders and the inner surfaces of said heads being parallel and being adapted to wedge with the tapered sides of said hooks when said bar is forced into said hooks, 40 and means for retaining said bar in said hooks.

3. In a draft rigging for railway cars, a pair 45 of draft sills, said sills being separated from their forward ends rearwardly for an appreciable distance to receive the draft rigging between them, a hook member formed integral with each of said sills adjacent its forward lower end, said hooks facing toward the forward end of said sills and opening at an angle above the horizontal, a single one-piece bar removably 50 mounted in said hooks for connecting and spacing said sills, means forming a wedging fit between said bar and said hooks, and means for retaining said bar in said hooks.

4. In a draft rigging for railway cars, a pair 55 of draft sills, said sills being separated from their forward ends rearwardly for an appreciable distance to receive the draft rigging be-

tween them, a hook member formed integral with each of said sills adjacent its forward lower end, said hooks facing toward the forward end of said sills and opening at an angle above the horizontal, a single one-piece bar removably mounted in said hooks for connecting and spacing said sills, means forming a wedging fit between said bar and said hooks, and means including lugs on the rear walls of said hooks and pins mounted in said hooks adjacent their points for retaining said bar in said hooks.

5. In a draft rigging for railway cars, a pair 60 of draft sills, said sills being separated from their forward ends rearwardly for an appreciable distance to receive the draft rigging between them, a hook member formed integral with each of said sills adjacent its forward lower end, said hooks facing toward the forward end of said sills and opening at an angle above the horizontal, an integral lug projecting from the 65 rear inner face of each of said hooks, said lugs having flat lower faces extending on an angle to the horizontal, a single one-piece bar removably mounted in said hooks for connecting and spacing said sills, said bar being cut away 70 adjacent each end to form bearing portions of reduced cross-section adapted to fit within said hooks and terminating at each end with parallel shoulder faces adapted to engage the sides of said hooks, said bearing portions being provided with a flat side adapted to be engaged against the flat lower faces of said lugs means forming a wedging fit between said bar and said hooks and pins secured in the points of said hooks to prevent displacement of said hooks.

6. In a draft rigging for railway cars, a pair 75 of draft sills, said sills being separated from their forward ends rearwardly for an appreciable distance to receive the draft rigging between them, a hook member formed integral 80 with each of said sills adjacent its forward lower end, said hooks facing toward the forward end of said sills and opening at an angle above the horizontal, a lug on the rear inner face of each of said hooks, said lugs having flat lower 85 faces extending on an angle to the horizontal, a single one-piece bar removably mounted in said hooks for connecting and spacing said sills, said bar being cut away adjacent each end to form bearing portions of reduced cross-section 90 adapted to fit within said hooks, said bearing portions terminating at each end with parallel shoulder faces adapted to engage the sides of said hooks, said bearing portions being cut away to clear said lugs and to form flat surfaces 95 adapted to engage the flat lower faces of said lugs by rotating said bar in said hooks, and removable means for preventing said bar from backing out of said hooks.
